UNITED STATES PATENT OFFICE.

IDA GREENWALD, OF NEW YORK, N. Y.

DESIGN FOR A PANEL FOR LIGHT-SHADES.

40,317.

Specification for Design.

Patented Oct. 19, 1909.

Application filed June 15, 1909. Serial No. 502,390. Term of patent 3½ years.

To all whom it may concern:

Be it known that I, IDA GREENWALD, a citizen of the United States, residing at New York, in the county of New York and State of New York, have invented a new, original, and ornamental Design for Panels for Light-Shades, of which the following is a specification, reference being had to the accompanying drawing, forming part thereof.

The figure is a perspective view, showing my new design.

I claim:

The ornamental design for a panel for light shades, as shown.

IDA GREENWALD.

Witnesses:

WILLIAM LEWIS,

CARL HENRY ENGELSTADTER.
